WALTHER AKEMANN, OF ESSEN, GERMANY, ASSIGNOR TO FRIED. KRUPP AKTIEN-
GESELLSCHAFT, OF ESSEN-ON-THE-RUHR, GERMANY.APPARATUS FOR COMPENSATING THE INACCURACY IN TRAINING A GUN, DUE TO THE
OBLIQUE POSITION OF THE AXIS OF THE HORIZONTAL TRUNNION.

Application filed December 3, 1920. Serial No. 428,112.

To all whom it may concern:

Be it known that I, Dr. WALTHER AKEMANN, residing at Essen, Germany, a citizen of the German Republic, have invented a 5 certain new and useful Improvement in Apparatus for Compensating the Inaccuracy in Training a Gun, Due to the Oblique Position of the Axis of the Horizontal Trunnions, for which I have filed an application 10 in Germany Dec. 12, 1917, and of which the following is a specification.

This invention relates to apparatus for the compensating on of the error in traverse caused by the oblique position of the horizontal axis of the trunnions of a gun. The 15 object of the invention is to provide an apparatus of this kind, which is particularly suitable for guns which are erected on a swaying foundation such as naval guns for 20 example. This object is attained according to the present invention by connecting an adjustable member which corresponds to the oblique position of the axis of the trunnions to a member which enables the traverse of 25 the gun barrel to be adjusted through the medium of a gearing which has a member which is adjustable to correspond to the angle of elevation of the gun barrel and the law of motion of which is determined ac- 30 cording to the relationship which exists between the oblique position of the axis of the trunnions and the angle of elevation of the gun barrel on the one hand and the error in the traverse on the other hand.

35 The invention will be further described with reference to the accompanying drawings in which two constructions of the invention are diagrammatically shown fitted with a long-distance indicating apparatus.

40 Figure 1 is the first and

Figure 2 is the second construction with certain parts omitted.

The gun barrel A, situated at the gun station, is mounted to oscillate by means of 45 horizontal trunnions a^1 in a gun carriage B which rotates about a vertical axis, and can be adjusted to the angle of elevation by means of an elevating gear (not shown).

On the gun carriage B is provided a ring of 50 teeth b^1 with which a hand wheel C, adapted to impart the adjustment of the traverse, is

positively connected through a gearing c^1 , c^2 , c^3 . To the hand wheel C are also positively connected the armatures of the transmitter D of a long-distance indicating apparatus built on the coarse and fine system. The coarse and fine armatures of the transmitter D are fitted with a pointer d^1 and d^2 respectively which pass over a traverse angle graduation. The transmitter D is connected to the corresponding receiver E by a long-distance conductor d^3 . The receiver E the coarse and fine armatures of which have a coarse and fine pointer respectively which indicate the position of the gun is 55 fixed to a frame E^3 which rotates about a vertical axis and on which a telescope F for marking the horizon is mounted to oscillate about a horizontal axis. The frame E^3 is 60 rotated about its vertical axis by a hand wheel G, which, on the one hand, is positively connected to two adjustable countermarks g^2 and g^3 opposite the receiver pointers e^1 and e^2 respectively. The apparatus 65 is so arranged that when in the position shown in the drawing, in which the countermarks g^2 and g^3 of the receiver E register with the corresponding pointers e^1 and e^2 and in which the frame E^3 consequently assumes the angular position prescribed by 70 the transmitter D, the axis of oscillation of the telescope F is crossing the axis of the horizontal trunnions a^1 at right angles. The telescope F is adjusted by a hand wheel H, the rotations of which are transmitted to the telescope F by means of a worm h^1 and a toothed sector h^2 gearing with it. If, 75 when the axis of the horizontal trunnions a^1 is in an oblique position the telescope F be trained upon the horizon by means of the hand wheel H, the angle which the telescope includes with the gun station is equal to the angle of the oblique position of the trunnions a^1 . To the shaft of the hand wheel H is positively connected, by a spur wheel 80 gearing $h^2 i^1$, one wheel J of a friction wheel gearing, the other wheel J^2 of which is mounted to move longitudinally along a shaft i^3 which is mounted at right angles to the axis of the wheel J, the shaft i^3 being mounted so as to rotate in the frame E^3 . The wheel J^2 is moved longitudinally by

means of a hand wheel K, the shaft k^1 of which, mounted to rotate in the frame E^3 , comprises for a portion of its length a screw spindle k^2 , on which latter is guided an arm 5 M provided with a screw nut m^1 and adapted to be moved longitudinally on the shaft k^2 with a forked end m^2 embracing the friction wheel gearing $J J^2$. On the shaft k^1 is also fixed a drum k^3 which carries a graduation k^4 corresponding to the angle of elevation of 10 the gun barrel and along which a reading-off mark k^5 is adapted to slide. The friction wheel gearing $J J^2$ thus forms a change speed gear in which the driven wheel J^2 is 15 adjustable to correspond to the angle of elevation of the gun barrel, while the driving wheel J undergoes a movement, which corresponds to the angle of the oblique position 20 of the telescope F and consequently of the axis of the trunnions. The angle of rotation of the driven friction wheel J^2 is proportional to the product of the angles of rotation of the two hand wheels H and K. The conditions for the friction gear $J J^2$ are 25 in particular so determined that the angle of rotation of the driven wheel J^2 is equal to the product of the angle of the oblique position of the telescope F and the angle of elevation of the gun barrel.

30 If the angle of correction of the traverse be denoted by ω , the oblique position of the axis of trunnions by γ and the elevation of the gun barrel by α then, as is well known

$$tg\omega = \sin \gamma \cdot tg\alpha$$

35 with great approximation.

If for the purposes of the present case the permissible simplification be used, viz. that of replacing the sine and tangent by the angles themselves or the values of their 40 arcs, it will be found that

$$\omega = \gamma \cdot \alpha$$

This condition, however, will be fulfilled by the arrangement described, as will be obvious without any further explanation.

45 The angle of rotation of the driven wheel J^2 is therefore equal to the angle by which the traverse of the gun has got to be corrected, in order to allow for the oblique position of the axis of its trunnions.

50 Upon the shaft $\tilde{v}$ is also keyed the transmitter J^4 of an electrical long-distance indicating apparatus, which transmitter J^4 is connected by a long-distance conductor to a receiver N which is mounted at the gun station and reproduces the rotary movements of the transmitter J^4 true to angle. The receiver N is provided with a pointer n^1 adapted to move over a disc P provided with a counter-mark p^1 , which disc P which 55 carries the counter-mark p^1 , is operated by a hand wheel p^2 positively connected to the disc P by a worm wheel gear. The hand wheel p^2 is also positively connected in the manner shown in the drawing to the one middle 60 wheel p^3 of a sun and planet gear, the other

middle wheel of which, b^2 , is positively connected to the ring of teeth b^1 on the gun carriage B and its planet wheel r^1 to a pointer R in the manner shown in the drawing. The pointer R is adapted to rotate 70 over the face of a disc S which is fixed and provided with traverse angle graduation. The ratios of transmission of the gearings leading from the hand wheel P^2 to the disc P and to the pointer R are equal to each 75 other, so that when the hand wheel P^2 rotates and the gun carriage B is stationary, the angles of rotation imparted to the counter-mark p^1 and the pointer are always equal to each other. Furthermore, the ratios 80 of transmission of the gearings connecting the hand wheel C to the gun carriage B and to the pointer R are equal to each other, so that when the hand wheel C is rotated and the hand wheel P^2 is stationary, each angle 85 of rotation of the gun carriage B is corresponded to by the same angle of rotation of the pointer R.

The explanation of the use of the apparatus above described will be begun from 90 the assumption that the gun barrel is in its zero position both as regards elevation and traverse and that consequently all the pointers and marks of the long-distance indicating apparatus are in the positions shown 95 in Fig. 1, in which in particular the axis of oscillation of the telescope F is located at right angles to the axis of the horizontal trunnions α^1 of the gun carriage A. Let it be also assumed that the ship is rolling, 100 which causes an inclination of the axis of the trunnions of the gun which is continually altered.

If now a prescribed traverse is to be imparted to the gun barrel and at the same 105 time the error in traverse caused by the inclination of the axis of the trunnions eliminated, the gun carriage is first adjusted to the prescribed angle of traverse by rotating the hand wheel C of the traversing gear, 110 which causes the transmitter D, which is positively connected to the hand wheel C to suffer a movement which is transmitted true to angle through the long-distance conductor d^1 to the receiver E. At the same time 115 the pointer R (which is positively connected to the hand wheel C) of the indicating apparatus R S sets itself to the division mark on the graduated disc S which corresponds to the angle of traverse.

The hand wheel G is then rotated according to the indications of the receiver E until the counter-marks g^2 and g^3 positively connected to the hand wheel G again coincide with the corresponding receiver 125 pointers e^1 and e^2 and the frame E^3 has consequently assumed together with the telescope F the traverse corresponding to the adjustment of the receiver. As soon as this is the case, the axis of oscillation of the 130

telescope F is again located at right angles to the axis of the horizontal trunnions of the gun barrel.

The graduated drum k^2 is now rotated by means of the hand wheel K until the mark k^3 points to the division mark of the graduation k^4 which corresponds to the prescribed elevation of the gun barrel, the arm M at the same time moving along the screw spindle 10 k^2 . The friction wheel β^2 carried by the fork m^2 consequently assumes the position required for the correct engagement of the friction wheels J and J^2 . If now the worm h^1 be rotated by the hand wheel H in such 15 a direction that the sighting line of the telescope F is permanently trained on the horizon during the rolling movement of the ship, the friction wheel J positively connected by the spur wheels h^2 i^1 to the hand wheel H 20 has imparted to it a rotation which is proportional to the angle of inclination of the telescope F, that is to say to the angle of the oblique position of the axis of the trunnions of the gun, and the said rotation is transmitted by friction to the friction wheel J^2 . The shaft i^2 and the transmitter J^4 keyed on it thus have imparted to them a movement which in consequence of the ratios of transmission selected is equal to the product of the 25 angle of the oblique position of the axis of trunnions and the prescribed angle of elevation of the gun barrel, and therefore equal, as above shown, to the angle to be added algebraically to this angle for the correction 30 of the angle of transverse.

In consequence of the movements of the transmitter J^4 the pointer n^1 of the receiver N mounted at the gun station is moved true to angle. The hand wheel P^2 is now so rotated that the counter-mark p^1 coincides permanently with the receiver pointer n^1 , which causes the middle wheel p^3 of the sun and planet gear p^3 r^1 b^2 positively connected to the hand wheel P^2 to be so moved that the 40 pointer R has a movement imparted to it which is equal to the movement of the counter-mark p^1 . As this movement (owing to the action of the sun and planet gear) is algebraically added to the movement previously imparted to the pointer R from the gun carriage B rotating about its axis of oscillation, the pointer R now coincides with a division mark on the graduation of the 45 graduated disc S, which is removed from the division mark corresponding to the prescribed traverse, by the same amount as the intended correction in the angle of traverse amounts to. By moving the hand wheel C of the traversing gear in such a way that the 50 pointer R returns to the value corresponding to the prescribed traverse, and remains permanently in this position, it is ensured that the gun possesses, at any moment, the traverse which has to be imparted to it after 55 allowing for the error caused by the oblique

position of the axis of its trunnions due to the rolling of the ship.

In the second construction of the apparatus the telescope which is intended to mark the horizon and is placed at an observing 70 station, is mounted on the stabilized shaft of a gyroscopic apparatus (not shown) contained in a casing F² and mounted on a column (not shown) adapted to rotate about a vertical axis. To the telescope F is positively connected the transmitter F³ of a long-distance indicating apparatus for the long-distance indication of the movements of the telescope F. The receiver F⁴ (connected to the transmitter F³) of the long-distance indicating apparatus intended for indicating the angle of inclination of the telescope F is provided with a pointer f⁵, coaxially with which pointer is mounted a worm wheel i⁶ provided with a counter-mark i⁷ and with 80 which a worm i⁸ rotated by a hand wheel J⁸ engages. To the worm shaft is rigidly connected one wheel J of the friction wheel gearing J J². The other wheel J² is mounted on a shaft i⁹ which is located at right 85 angles to the axis of the wheel J and cannot rotate thereon but can move longitudinally along it. This longitudinal movement is rendered possible by an arm M, which terminates in a fork m² and is guided 90 by its end which comprises a screw nut m¹ on a screw spindle k² parallel with the axis of the wheel J², which screw spindle k² can be set to the angle of elevation of the gun barrel by means of a hand wheel K. The movement imparted to the screw spindle k² and consequently to the friction wheel J² is indicated by a reading-off device, which consists of a drum k³ mounted on the spindle and provided with an elevation angle graduation 95 k⁴, and a reading-off mark k⁵ movable longitudinally along this graduation.

On the shaft i⁹ is keyed the one middle wheel i¹⁰ of a sun and planet gear i¹⁰ r^1 w^2 the other middle wheel of which, v¹, is positively connected through a pair of spur wheels to a telescope V adapted to rotate about a vertical axis and intended to point at the target, while the planet wheel w² is mounted on the rectangularly bent end of 110 a shaft w³ which is positively connected through a pair of bevel wheels to the driving shaft w⁴ of the transmitters W and W¹ of long-distance controlling apparatus built on the coarse and fine system. The driving shaft 115 w⁴ is positively connected to the coarse transmitter W by a worm gear and to the fine transmitter W¹ by a toothed wheel gearing. From the two transmitters W and W¹ long-distance conductors w⁵ and w⁶ lead to 120 the receivers (not shown) which are provided for the long-distance controlling apparatus for the angle of traverse of the gun and are mounted at the gun station.

For the consideration of the working of 125

the second construction shown in Fig. 2 let it be assumed that the sighting line of the telescope V is parallel with the sighting line of the gun telescope trained laterally on the target and the telescope F which is adapted to point at the horizon crosses the sighting line of the telescope V at right angles. If now the gun to be laid is to receive the traverse corresponding to the momentary oblique position of the axis of the trunnions, the telescope F which is situated at the observing station and stabilized by the gyroscopic apparatus contained in the casing F^2 is adjusted to the horizon. By the adjustment of the sighting telescope F on to the target to be fired at, the one middle wheel, r^1 , of the sun and planet gear $r^1 w^2 p^0$ has imparted to it a rotation, which corresponds to the angle of traverse of the sighting telescope V now trained on the target. The hand wheel K is now rotated until the angle of elevation to be imparted to the gun is adjusted on the reading-off apparatus $k^1 k^2$ and the friction wheel J^2 has correspondingly undergone a movement corresponding to the angle of elevation of the gun barrel. Since the telescope F maintains its angle adjusted to the horizon under the action of the gyroscopic apparatus, there arises, for example when the ship is rolling, between the said telescope and its bearing member relative oscillations the magnitude of which any instant are equal to the particular oblique position of the axis of the trunnions. These relative oscillations are transmitted by means of the long-distance indicating apparatus $F^2 F^4$ on the receiver pointer f^3 in such a way that it makes corresponding oscillatory movements relatively to the counter-mark f^1 . If now the hand wheel J^2 be so rotated that the counter-mark positively connected thereto (i^2) permanently registers with the receiver pointer f^3 an angle of rotation is transmitted through the medium of the friction gearing J^2 to the other middle wheel r^0 of the sun and planet gear $r^0 w^2 v^1$ the magnitude of which is proportional at any moment to the product of the particular existant angle corresponding to the oblique position of the axis of the trunnions and the angle of elevation of the gun. The planet wheel w^2 of the sun and planet gear and consequently the driving shaft w^1 of the coarse transmitter W driven thereby and also that of the fine transmitter W^1 accordingly make a rotation which, with the selected ratios of transmission, is equal to the algebraic sum of the angles of rotation of both the middle wheels v^1 and v^0 . As however one of these angles of rotation corresponds to the angle of traverse of the sighting telescope V and consequently of the gun to be laid and the other corresponds to the angle by which the angle of traverse of the gun has got to be corrected in order to eliminate the influence of the

oblique position of the axis of the trunnions, it follows that the transmitters rotated by the driving shaft w^1 suffer a movement, under the ratios of transmission selected, the magnitude of which corresponds at any moment to the angle of traverse of the gun altered by the angle of correction corresponding to the oblique position of the axis of the trunnions. The angle of traverse of the sighting telescope V altered by the angle of correction is passed further on to the coarse and fine receivers (not shown) situated on the gun so that this latter can be adjusted by referring to the indications of the receiver directly to angle of traverse altered by the angle of correction.

The second construction affords in comparison with the first construction the advantage of greater readiness for fire. This results first from the fact that the gun can be fired not only on the points of reversal of the rolling movement, in which alone an accurate adjustment of the telescope to the horizon is possible, but at any desired moment as the telescope, once it has been adjusted to the horizon, can be permanently kept trained on the horizon by the aid of the gyroscopic apparatus. The increased readiness for fire is secondly based upon the fact that the correction of the angle of traverse has not to be transmitted to the gun station and there utilized for the adjustment of the indicating apparatus for the angle of traverse, but that the corrected angle of traverse can be read off at the gun station at once and the gun laid accordingly. This is of special importance when the elevating gear of the gun is to be driven through the receiver of the long-distance controlling apparatus directly or through the medium of an auxiliary motor.

Without departing from the spirit of the invention there may be used in the construction shown in Fig. 1 instead of the indicating apparatus $R S$ an indicating apparatus which has two coaxial parts adjustable relatively to each other. One of these, a pointer for example, is positively connected to the receiver of a long distance indicating apparatus, which is intended to indicate the traverse to be imparted to the gun, and the other, a rotating disc provided with a counter-mark for example, is connected to the shaft of the planet wheel r^1 while of the corresponding middle wheels r^0 of the sun and planet gear $p^3 r^1 b^2$ one, b^2 , is positively connected to the gun carriage B and the other, p^3 , to the hand wheel F^2 which serves to move the counter-mark p^1 .

In this case it is only necessary to rotate the hand wheel F^2 so that the counter-mark p^1 is kept permanently in register with the receiver pointer p^3 of the long-distance indicating apparatus acted on by the friction wheel gearing, and to so move the elevating

gear of the gun by means of the hand wheel C that the pointer and the counter-mark of the indicating apparatus for the traverse assumed by the gun also permanently register with each other.

Furthermore there might be used in the apparatus which form the subject matter of the present invention instead of the telescope intended to point at the horizon a rocking spirit level the axis of oscillation of which intersects the axis of the horizontal trunnions at right angles.

I claim:

1. An arrangement of the class described for guns for correcting the errors in traversing caused by inclination of the horizontal trunnion axis of the gun comprising means adjustable in accordance with the inclination of the axis of the gun trunnion, means for indicating the traverse to be imparted to the gun, a distance control device embodying gearing for connecting said first mentioned means to said last mentioned means, and means connected to a part of said gearing for adjusting the same in accordance with the elevating angle of the gun whereby the traverse indicating means has imparted thereto the product of the angle of inclination of the trunnion axis and the prescribed elevating angle of the gun.
2. The combination with a gun provided with horizontal trunnions of an arrangement for correcting errors in traversing caused by inclination of the trunnion axis comprising means adjustable in accordance with such inclinations, an indicating device for indicating the angle of traverse to be imparted to the gun, distance transmission embodying gearing for connecting said first mentioned means to said indicating device, said gearing comprising friction members relatively adjustable and means adjustable in accordance with the elevating angle of the gun for adjusting said friction gearing, the degree of said adjustment being so selected as to correspond to the relation existing between the inclination of the axis of the gun trunnions and the elevating angle of the gun, whereby the adjustment transmitted to the indicating device indicates the correction necessary to correct the traversing angle and is the product of the angle of inclination of the trunnion axis and the prescribed elevating angle of the gun.
3. The combination with a gun provided with a horizontal trunnion axis of an arrangement for correcting errors in traversing caused by inclination of the trunnion axis comprising a stand located at an observation station and revoluble about an upright axis corresponding to the axis about which the gun is traversed, means mounted on said stand and adjustable in accordance with the inclination of the gun trunnion axis, a distance indicating apparatus connecting
- said gun with said rotatable stand whereby said stand may be rotated to bring the axis of oscillation of said adjustable member to intersect the trunnion axis perpendicularly, a variable gearing carried by said stand, means connecting one part of said gearing with said adjustable member and means for adjusting the other part of said gearing in accordance with the elevation angle of the gun, an indicating means arranged adjacent the gun and an electrical distance control means connecting said variable gear with said indicating device whereby the product of the angle of inclination of the gun trunnion axis and the prescribed elevation angle of the gun may be transmitted to said indicating device to indicate the correction necessary to be made to the traversing angle for improving the same.
4. The combination with a gun provided with horizontal trunnions and a carriage rotatable about an upright axis of an arrangement for correcting errors in traversing the gun caused by inclination of the horizontal trunnion axis of the gun, said arrangement comprising a telescope adapted to intersect the horizon, a friction gearing comprising two parts, means connecting one part of said gearing to said telescope, means for adjusting the other part of said gearing to the angle of elevation of the gun, an indicating device arranged adjacent the gun and comprising two adjustable marks, a receiver forming part of an electrical distance transmission for adjusting one of said marks, said distance transmission being connected with said friction gearing, a second indicating device provided with an adjustable part, means including a planetary gear for connecting said adjustable part with the gun carriage so that said second indicator will indicate the angle of traverse of said gun and means for connecting the adjustable part of said second indicator with the other mark of said first mentioned indicator.
5. The combination with a gun provided with horizontal trunnions and a carriage rotatable about an upright axis of an arrangement for correcting errors in traversing the gun caused by inclination of the horizontal trunnion axis of the gun, said arrangement comprising a telescope adapted to intersect the horizon, an adjustable friction gearing, means connecting said telescope to one part of said gearing, means for adjusting the other part of said gearing in accordance with the angle of elevation of the gun, an indicating device arranged adjacent the gun and comprising two co-axial members adjustable relatively to one another, a receiver forming a part of an electrical distance control for adjusting one of said members, said distance control means being connected to said friction gearing, a second indicating device, an adjustable member form-

ing a part of said indicating device, said adjustable member being connected to the gun carriage by a planetary gear, said indicating member being adjustable independently of the position of the gun carriage and of the position of an opposing mark showing the traversing error.

The foregoing specification signed at Esen, Germany, this 16th day of June, 1920.

DR. WALTHER AKEMANN.
